CLAIM

The ornamental design for a display screen with an animated computer icon, as shown and described.

DESCRIPTION

FIG. 1 is a front view of a first image in a sequence of a display screen with an animated computer icon; and, FIG. 2 is a front view of a second image in the sequence thereof.

The appearance of the graphical user interface sequentially transitions between the images shown in FIGS. 1-2. The process or period in which one image transitions to another image forms no part of the claimed design.

The outermost broken line illustrates a display screen that forms no part of the claimed design.
